UNITED STATES PATENT OFFICE.

FELIX FRED DANIELS, OF JERSEY CITY, NEW JERSEY.

SNOW-REMOVER.

1,398,454.

Specification of Letters Patent. Patented Nov. 29, 1921.

Application filed June 10, 1920. Serial No. 387,840.

To all whom it may concern:

Be it known that I, FELIX FRED DANIELS, a citizen of the United States, residing at Jersey City, in the county of Hudson, State 5 of New Jersey, have invented certain new and useful Improvements in Snow-Removers; and I do hereby declare the following to be a full, clear, and exact description of the invention, such as will enable 10 others skilled in the art to which it appertains to make and use the same.

This invention relates to excavating, and more especially to snow road machines; and the object of the same is to produce a motor 15 driven machine for scooping the snow from a street or road, melting it, and washing the surface with the water thus produced.

A feature of the invention lies in keeping the parts constantly warm so that the snow 20 will not stick to them and choke or clog the machine.

A striking feature of the invention is its simplicity, the whole being built on the frame of a motor truck capable of being 25 driven by one man.

Details are set forth below and shown in the drawings wherein:

Figure 1 is a side elevation of this machine partly broken away and in section.

Fig. 2 is a plan view.

Fig. 3 is a detail of part of the conveyer.

The motor truck herein comprises wheels W carrying a frame F and a cab C for the driver. All these parts may be of the usual 30 construction, excepting that the wheels should have rather wide treads and the cab is by preference set well toward the left of the frame F as seen in Fig. 2.

Brackets 1 project from the frame F 40 forward, and pivoted between them at 2 is a scoop 3 having a wide mouth and converging side walls. An ear 4 rises from its rear end, and a chain 5 leads from this ear to a point within reach of the driver, 45 being here shown as wound on a drum or pulley 6 which when turned by him will cause the rise or fall of the front scraping edge 7 at the mouth of the scoop 3. Obviously this edge should travel upon or very 50 nearly in contact with the surface of the road or street, so as to gather the snow and ice therefrom; and if the parts be built of proper size and strength, this machine can scoop the snow off of half the width of 55 a street when moving in one direction, and clean the other half on its return trip.

The snow gathered by the scoop is delivered into a box 10 which forms the casting of a carrier leading from the rear end of the scoop obliquely upward, and preferably disposed somewhat to the right of the frame F so as to pass the cab C and permit the operator in the latter to have an unobstructed view forward. Mounted within said box are chains 11 carrying buckets 60 or blades 12 by which the snow is moved upward, this carrier being driven through a belt 13 connecting a pulley 14 on its upper shaft with a pulley 15 on some shaft of the motor, as the counter shaft 16, which, as 65 seen in Fig. 2, is belted to the rear wheels.

The rear end of the box 10 connects with a chute 20 which inclines downward and rearward and delivers into the mouth of the hopper 21, the walls of the latter converging to its extreme lower end and being here connected with pipes 22 leading to sprinkler heads 23 located in front of the driving wheels as shown in the drawings, although their exact construction and location is immaterial; and in this manner the water produced by melting the snow and ice within the hopper is delivered back onto the roadway so as to wash from it any snow or particle of ice which may remain, or possibly to wash the surface of the street itself. If the water is delivered just in front of the rear or drive wheels, the cleansing of the surface will prevent them from slipping. If the machine is used 70 on a road or on a street having a soft surface, it may be wise to divert one or both of the outlets 23, or to replace them by nozzles so that the water will be delivered at the sides of the road or in the gutters along 75 the sides of the street. This entire structure is supported on the frame F in rear of the cab C, and back of the hopper the frame may carry a fire-proof partition or wall 24, as of asbestos. In rear of this, in 80 turn, the frame carries a large gasoline tank 25 having a filling opening 26; and a roof 27 overlies the tank and the hopper, and may extend partway over the conveyer.

A highly important feature of this invention lies in the fact that, from the moment the snow and ice is gathered, it is subjected to heat having in increasing affect thereon by reason of the nature of its application. As herein shown, a gasoline pipe 105 30 leads from the tank 25 forward and is connected with one or more burners in the

shape of pipes 33 underlying the scoop 3 so that the bottom of the same and the rear portions of its side walls are heated. From said pipe 30 a branch 34 leads to other burners 35 disposed below the box 10 constituting the body of the carrier or conveyer, so that the latter is heated. From said pipe 30 also a branch 36 rises to a large burner 37 which surrounds the wall of the hopper 21 forward of the asbestos wall 24, and the hopper is thereby heated considerably. The effect will be that the warmth given to the scoop will prevent the snow and ice from choking or clogging the same, the warmth imparted to the conveyer will have the same result upon it, and the heat imparted to the wall of the hopper will rapidly melt the snow and ice therein so that it runs out the pipe or pipes 22 in the form of water. Provision will be made for cutting off or regulating the supply of gasoline to these various heaters, as well as for regulating the outlet of water and controlling the other units of the machine. Also gasoline can be taken from the pipe 25 for driving the motor engine.

What is claimed is:

1. In a snow remover, the combination with a motor truck having a gasoline tank at its rear, and a driver's cab disposed at one side of the framework; of brackets at the front end of the truck, a scoop hinged

thereon, means for pivotally adjusting the scoop from the cab, a carrier leading from the rear end of the scoop upward alongside the cab, an upright hopper carried by the frame in rear of the cab, a chute leading from the upper end of the carrier into the hopper, and means for imparting heat to said hopper to melt the snow therein and for delivering the melted snow onto the road.

2. In a snow remover, the combination with a motor truck having a gasoline tank at its rear, and a driver's cab disposed at one side of the framework; of brackets at the front end of the truck, a scoop hinged thereon, means for pivotally adjusting the scoop from the cab, a carrier leading from the rear end of the scoop upward alongside the cab, an upright hopper carried by the frame in rear of the cab, a chute leading from the upper end of the carrier into the hopper, a burner surrounding the hopper, heaters underlying the scoop and carrier, and a gasoline pipe leading from the tank and branched to the burner and heaters.

In testimony whereof, I affix my signature, in the presence of two witnesses.

FELIX FRED DANIELS.
